Patented Nov. 21, 1961

191,791

BOWLER'S BENCH

Richard L. Konves, 34 W. Maxwell Drive, Shelby, Ohio

Filed Apr. 26, 1961, Ser. No. 64,908

Term of patent 14 years

(Cl. D34—5)

FIG.2

FIG.1.

I claim:

The ornamental design for a bowler's bench, as shown.
